ROOF

Kenneth E. Bemis, Jr., 5400 Linden Drive,
Bethesda, Md.

Filed July 19, 1967, Ser. No. 7,879

Term of patent 14 years

(Cl. D13—1)

Fig. 1.

Fig. 2.

The dotted lines in FIG. 1 are disclosed for illustration purposes only.

I claim:

The ornamental design for a roof, as shown and described.
